DISPENSER CAP FOR A PRESSURIZED CAN

Nathan Berman, Havertown, Pa., assignor to Renuzit Home Products Co., Philadelphia, Pa., a corporation of Pennsylvania

Filed Apr. 11, 1966, Ser. No. 1,833

Term of patent 14 years

(Cl. D58—26)

FIG. 1.

FIG. 2.

FIG. 3.

FIG. 4.

FIG. 5.

FIGURE 1 is a perspective view of a dispenser cap for a pressurized can embodying my new design;

FIGURE 2 is a front elevational view thereof;

FIGURE 3 is a rear elevational view thereof;

FIGURE 4 is a side elevational view thereof; and

FIGURE 5 is a top plan view.

Portions of the cap are shaded and stippled to indicate contrasting surface texture rather than to indicate any particular color.

I claim:

The design for a dispenser cap for a pressurized can, substantially as shown and described.
